UNITED STATES PATENT OFFICE

2,004,579

REINFORCED TENNIS NET AND METHOD
OF MAKING THE SAME

Valentine Lichtenstein, Jersey City, N. J., assignor
to The Fish Net and Twine Co., Jersey City,
N. J., a corporation of New Jersey

Application August 23, 1932, Serial No. 630,001

6 Claims. (Cl. 273—29)

My invention relates to improvements in double center and heavy center tennis nets and to the method of making the same.

Double center tennis nets have been constructed which include three substantially rectangular sections, namely, a center section of double strand netting and two outside or end sections of single strand netting. This type of tennis net is assembled by lashing the ends of the side sections to the ends of the center section with the result that the finished product is a net having rows of unsightly knots and loose ends marking the seams between the center and side sections.

With the foregoing in mind it is the purpose of my invention to produce a tennis net which will embody in its structure a double or heavy center portion and single side portions and which will not be marked by any knots or loose ends along the lines between the single and double or heavy portions.

It is a further purpose of my invention to provide a tennis net which consists of a single strand netting at its outer ends and reenforcing double or heavy strand netting at its mid section, the latter being composed of a triangular shaped insert and side portions forming a symmetrical perfectly balanced double or heavy center built into the net structure.

I accomplish this purpose by utilizing a novel method of constructing a tennis net according to the present invention, the steps employed being described in the following specification, set forth in the appended claims and illustratively exemplified in the accompanying drawing, in which, Figure 1 is a front elevational view of a tennis net as it appears on the court; Figure 2 is an elevational view of a length of the netting, as it comes from the knitting machine, embodying the reinforced double strand sections at the sides; Figure 3 is an elevational view of a net after it has been squared and separated from the original length; Figure 4 is an elevational view of the parts of the net as they would appear during the step of reversing certain of the parts and inserting a center section; Figure 5 is an elevational view of a length of squared netting where the double strand section is disposed originally in the mid section; and Figure 6 is an elevational view of the same length after severing it transversely thereof and reversing one half to form the finished net. Figure 7 is an elevational view of a portion of the wedge or insert showing the loop ends along the sides; and Figure 8 is an elevational view of a section of the finished net show-

ing the seam formed by joining the wedge and adjacent side of the V-shaped opening between the two sections of the net.

According to the present invention my improved method of constructing a tennis net, consists in knitting a length of so-called diamond shaped netting with a single strand longitudinal central portion and a double or heavy strand narrower portion along each side. The netting is squared in the usual manner by separating the mesh diagonally across the full width of material, as illustrated in dot-and-dash lines in Figure 2. The squared strip of netting then consists of substantially three parallelograms, namely, a relatively long single strand mid section and two double strand end sections. The strip is severed transversely thereof along a center line of the mid-section, as shown in dot-and-dash lines in Figure 3. The next steps consist first in reversing one of the severed portions so that the double strand end section is disposed adjacent and aligned with the double strand end section of the other end, and second, in inverting one of the severed portions to bring the diagonal ends of the two double strand sections into position to form a V-shaped opening therebetween, as shown in Figure 4. A double or heavy strand triangular dart or wedge is then knitted and placed in the V-shaped opening of the net.

At this point in the construction of the net it must be noted that the diagonal ends of the double or heavy mesh sections are just as they come from the knitting machine, i. e. with the end loops free along one side. The triangular shaped dart is also knitted with the loops free along the sides as shown in Figure 7, so that when it is placed into the V-shaped opening between the two double mesh end sections the free loops of each piece will be spaced apart one square and connected together by running a strand or strands of twine from side to side in a stepped line to engage the points of the loops and at each point tying in a knot without loose ends to fasten the loops in position as shown in Figure 8. Because the strand used to connect the pieces of netting together follows exactly the outline of the knitted strands, in the sections it is very difficult to see where the lines of the connection have been made. The outline of the triangular dart is indicated in dot-and-dash lines in Figure 1.

It will be clear that in accordance with the several steps of the method outlined above it is possible to produce a tennis net having a double strand or heavy center portion evenly di-

vided on opposite sides of the vertical center line of the net proper and outside single strands sections running from opposite ends of the double strand section to the ends of the net.

5 Referring now to the finished product, reference will be had to the drawing, in which 10 denotes the single strand end sections of the tennis net, each thereof terminating at its inner end in a parallelogram shaped double strand section 11. The free sides 12 of sections 11 when placed adjacent to each other form a V-shaped opening 13, the sides 12 of the opening comprising a series of loops 14, as illustrated in Figure 8. A triangular shaped insert or dart 15 is constructed of double or heavy strand netting having a row of loops 16 with free sides disposed about its two sides. The number of loops 14 of the sides 12 correspond with the number of loops 16 of one side of the insert or dart 15 so that a strand or strands 17 of twine may be run along from side to side engaging the corners of the loops at each lower step. A knot 18 is tied at each meeting point with a loop to attach the two double sections 11 of the outside sections 10 to the insert or dart 15. In the usual manner the upper and lower sides of the net are attached to separate ropes 19 or lengths of binding material which extend beyond the ends of the net for the purpose of attaching it to the posts of the court.

The finished net, as it appears in Figure 1, consists of a substantially inverted trapezoidal shaped double or heavy strand center section and single strand end sections.

35 In order to accomplish a somewhat similar result in the construction of reenforced tennis nets and to avoid the more costly steps in the manufacture of the preferred embodiment of my invention outlined above, I have devised a net illustratively exemplified in Figures 5 and 6, in which the ordinary net, having a diagonally disposed mid section 20 of double strand netting, is merely severed along a transverse center line 21 shown in dotted line in Figure 5, leaving two halves 22, one thereof being inverted, and their raw edges attached so as to construct an inverted trapezoidal shaped double strand center section 23 and outer single strand sections 24. The seam formed by attaching the raw edges together is concealed within a tape covering 25, as illustrated in Figure 6. The net constructed according to this modified form of my invention has the same general appearance as that of the preferred form except that the transverse center line of the net is marked by the upright tape covering 25.

Having now described my invention and the method by means of which the invention is constructed, what I claim and desire to secure by Letters Patent is:

60 1. The herein described method of producing a centrally reenforced tennis net, which consists in squaring a strip of diamond netting having a single strand mid portion and heavy strand side portions to procure a strip having alternate parallelogram shaped sections of single and double strand netting, severing the single strand portion along a center line running transversely of the net, arranging the severed pieces of the netting 65 to bring the free sides of the double strand portions into position to form a V-shaped opening therebetween, and thereafter filling out the opening with a heavy strand section to form a continuous netting.

2. The herein described method of producing a centrally reenforced tennis net, which consists in squaring a strip of diamond netting having a single strand mid portion and double strand side portions to procure a strip of alternate parallelogram shaped sections of single and double strand netting, thereafter severing the single strand portion along a center line running transversely of the net, bringing the free ends of the double strand portion adjacent each other and inverting one of the portions to cause a V-shaped space to be formed between the free ends, constructing a triangular shaped piece of double strand square netting and placing the same into the V-shaped space, and knitting twine into the 10 adjacent sides of the sections to attach the triangular piece to the adjacent free sides of the double strand sections.

3. A tennis net of the character described, comprising a length of squared netting having a trapezoidal shaped mid portion of heavy strand netting, a part of the integral side portions of single strand netting, said length of netting consisting of at least two separate pieces connected together, a part of each of said pieces being included in the portion of heavy strand netting, and the said trapezoidal shaped mid-portion of heavy strand netting being disposed with its smaller parallel side at the lower edge of the tennis net.

4. A tennis net of the character described, comprising a length of squared netting having two parallelogram shaped heavy strand sections forming the sides of a V-shaped central opening, and a triangular shaped wedge of heavy strand netting disposed in said opening and integrally attached along its sides to the sides of the opening said length of squared netting consisting of two separate pieces connected together and each thereof carrying a parallelogrammic shaped heavy strand section.

40 5. A tennis net of the character described, comprising a length of squared netting having two rhomboidal shaped double strand sections forming the sides of a V-shaped central opening and an integral extension of each section formed of single strand netting, to form the outer ends of the net, a triangular shaped wedge of double strand netting disposed in said opening, said length of squared netting consisting of two pieces connected together and each thereof carrying 45 one of said rhomboidal shaped double strand sections, and strands of twine integrally attaching the sides of the opening to the sides of the wedge.

6. A tennis net of the character described, comprising two sections of square netting, each thereof having a rhomboidal shaped double or heavy strand end portion and a single strand portion extending therefrom, the adjacent ends of the double or heavy strand portions forming a V-shaped opening, the sides of which comprise a 60 series of loops each being free along one side, a triangular shaped double or heavy strand netting in said opening having two of its sides formed with loops each being free along one side and spaced one square from the free side of a loop of 65 the double or heavy strand portions, and a length of twine or twines running from side to side and in a downward direction between the adjacent points of the spaced loops, the twine being knotted to the said points to form a continuous net.
